United States Patent Office.

HORACE BOARDMAN, OF PORT RICHMOND, NEW YORK.

Letters Patent No. 100,847, dated March 15, 1870.

IMPROVEMENT IN STEAM-ENGINE GOVERNORS.

The Schedule referred to in these Letters Patent and making part of the same.

To all whom it may concern:

Be it known that I, HORACE BOARDMAN, of Port Richmond, in the county of Richmond, in the State of New York, have invented a new and improved Governor; and I do hereby declare that the following is a full, clear, and exact description of the construction and operation of the same, reference being had to the annexed drawings making a part of this specification, in which—

Figure 1 is a half side elevation and half vertical section.

Figure 2, a plan.

Figure 3, a transverse section on the line P Q.

The nature of my invention consists in a new mode of communicating and transmitting or conveying a rotary or circular motion by the use of the revolving cylinder A, having a corrugated inside surface, B, the cylinder-heads C C' with radial ribs E, which, when secured to the cylinder A, form a chamber, which is filled with a fluid.

When the cylinder A is set in motion, the fluid acts as a communicating medium on the winged center D, and has a strong tendency to revolve the winged center D in the same direction.

This winged center D is made fast to the center spindle F, on the upper end of which is a pulley, G. This pulley G has wound around it a cord, which is connected to the valve-gate or other apparatus intended to be regulated; or it may be connected by a crank-gear or other well-known devices for connecting a governor to its work.

The valve or other apparatus is intended to be weighted open, and when the cylinder A is running at a certain speed, the power communicated to the winged center D will balance the weight. Any change from

this speed will change the position of the weight, and also the position of the connected apparatus in either direction.

The power is applied to the shaft H, by means of a belt or gearing connected to the prime motor, and transmitted to the cylinder A by means of the miter-gears I I' and hollow spindle J.

K is the main frame or stand, with its necessary bearings.

L is a pivot-plug screwed into the lower head C' of cylinder A. This pivot-plug L centers and forms a bearing for the lower end of center spindle F, and also has a bearing in the socket M. This socket M is secured to the frame K, and set in its proper place by means of the binding-nuts N N'.

O is a crank made fast to the shaft H, for the purpose of showing the operation of the governor.

This governor is intended to be used to control the speed of a steam-engine, water-wheel, or any other prime motor, by connecting the same in such a manner that that motion, shall be communicated from the motor to the revolving cylinder A, or its equivalent, and be transmitted through the fluid medium to the winged center D and its connections, to the regulating apparatus.

What I claim as my invention, and desire to secure by Letters Patent, is—

The revolving cylinder A and its combinations, constructed and arranged substantially in the manner and for the purposes herein specified.

HORACE BOARDMAN.
